UNITED STATES PATENT OFFICE

GEORGE TRAUTVETTER, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA

CONSTRUCTION AND METHOD OF ASSEMBLY OF SHEET METAL DOORS

Application filed June 27, 1928. Serial No. 288,712.

This invention relates to sheet metal door construction and to a method of assembly of doors so constructed out of sheet metal, the invention being particularly adapted for use 5 in connection with doors of the class shown in Ledwinka application Serial No. 230,703 for automobile door, filed November 3, 1927.

It is an object of my invention to construct a door of this class made of relatively few 10 major stampings, comprising outer and inner panel stampings and opposed glass run channel stampings each extending around the window opening of the door, in which the stampings are relatively simple and in which 15 they are so conformed as to be readily brought together in assembled relation for the speedy assembly of the same; and to combine them in such order and in such sub-assembly units as to render their assembly very easy and rapid; 20 and finally, to make the door so constructed and assembled exceedingly strong, rigid and durable even if constructed, as contemplated, of relatively light gauge stampings, and in which substantially all joints are hidden so 25 that substantially no finishing operations are required on the door so assembled.

In the accompanying drawings I have shown one embodiment of a door constructed and assembled with a view to the accomplishment 30 in a very high degree of the objects of the invention above-mentioned in them.

Fig. 1 is an outside elevational view of a 35 door constructed and assembled according to the invention.

Figs. 2, 3, 4 and 5 are detail sectional views taken on the respectively numbered lines of Fig. 1.

Figs. 6 and 7 are sectional views similar to Fig. 3 illustrating an intermediate stage of 40 the assembly.

Fig. 8 is a sectional view similar to Figs. 6 and 7 showing the final stage of the assembly of the bringing together and joining of the parts shown separately in Figs. 6 and 7.

The door of my invention is comprised in the main of four unitary stampings, an outer panel stamping 10, and inner panel stamping 11, and outer and inner glass run channel frame stampings 12 and 13, respectively, 50 each extended around the window opening in

the door. The outer and inner panel stampings are given the form and extent of the door as in the prior construction above referred to, the inner panel being laterally extended to provide the jamb face portions 14 of the door and the outer edges of the jamb face portions are flanged as at 15 to form the door overlap.

In the margins of the window opening the outer and inner panel stampings are respectively, provided with angular seats 22 and 23 and beyond said seats with flanges 16 and 17, which prior to assembly extend transversely of the bodies of the panel stampings as indicated in dotted lines in Figs. 6 and 7, but are crimped down over the adjacent edge of the glass run channel stampings in the final assembly, as shown in full lines in the drawings.

The glass run channel stampings are generally of channel cross section, particularly 70 in their side and top portions, the channels facing toward the central plane of the door. The side walls 18 and 19 of the inner and outer channel stampings arranged adjacent the window openings are inclined to conform 75 with the contour of the adjacent panel stamping and are flanged respectively, at 20 and 21, substantially parallel to the plane of the door, thereby forming angular seats 24 and 25 nesting respectively, with the angular seats 22 and 23, respectively, formed on the outer 80 and inner panel stampings. The outer walls 26 and 27 of the generally channel-shaped stampings 12 and 13 are extended, in their tops and sides, parallel to the jamb face portions of the inner panel, and secured thereto. At the hinge and lock sides of the door they 85 overlap each other through a substantial area to provide a strong joinder not only to each other but also to the jamb face portions of the inner panel. At the lock side, the jamb rail portion is rabbeted at 33 and the inner glass rim stamping has its outer side wall 27 formed with a flange 27' providing an angular seat which nests with the rabbeted portion 90 33 of the jamb rail portion of the inner panel stamping.

At the top the outer side walls 26 and 27 are not deeper in this region than the inner side walls of the channel sections and are 100

secured to the jamb face portion of the inner panel on opposite sides of the slot 28 provided in said jamb face portion to permit the removal or insertion of the window glass 5 through the top of the door.

At the bottom the side wall of the channel at the outside face of the door may be, as shown in Fig. 5, nothing more than a slight offset 29, at the inside of the door the channel section is opened out so that the side walls 19 and 27 lie against the angularly related surfaces 30 and 31 of the inner panel stamping at the bottom of the window opening and are secured thereto. The glass run stamping 15 thus forms with the inner panel a box section structure which strengthens the door in this region.

The door construction as described is very conveniently and expeditiously assembled by the following method, and when assembled, forms a very strong, rigid and durable door, which is yet light in weight because made of relatively light gauge sheet metal stampings.

By this method of assembly, the inner and outer glass run channel stampings 12 and 13 are first brought into a nested relation with the outer and inner panel stampings 10 and 11 respectively, this as indicated by the sectional views. In the case of the outer panel stamping 10 and the adjacent glass run stamping 12, the angular seat 22 of the outer panel extending around the window opening nests readily with the angle formed by the side wall 18 and edge flange 20 of the channel section glass run stamping when the parts are brought together as in an assembly jig, and the outer panel 10 and outer glass run channel stamping 12 are then readily and firmly secured together by crimping down the flange 16 from the dotted line position to the full line position in which its edge 16' engages the inside surface of the side wall 18 of the channel stamping, and thus securely locks the joined elements together to form the unitary sub-assembly, a typical section of which is shown in Fig. 7.

Similarly, the inner panel stamping 11 and the inner glass run stamping 13 are readily brought together as in a suitable assembly jig, so that the angular seat 23 nests with the adjacent angular portion 18, 21 of the glass run stamping and the outer channel wall seats against the jamb face portion 14 of the inner panel at top and sides, the angular portion 27, 27' of the stamping, see Figs. 3 and 6, nesting with the rabbeted portion 33 of the jamb face portion 14 at the lock side of the door. The parts 11 and 13 are then securely joined to form the unitary sub-assembly shown by the typical section shown in Fig. 6 by spot welding the outer channel wall 27 to the jamb face portion 14 of the inner panel at sides and top and by crimping 65 the flange 17 of the inner panel down over

the flange 21 and adjacent portion of the side wall 19 to form the locked clamped joinder in a manner similar to that described above in connection with the outer panel and its adjacent portion of the sub-assembly. At the 70 bottom of the window opening, joinder is further effected by spot welding the side wall 27 of the opened channel section portion at the bottom of the window glass run stamping to the body portion of the inner panel 75 at 31, thereby forming the box section structure above referred to.

The door is finally assembled by bringing the two unitary outer and inner sub-assemblies represented by the typical sections of Figs. 6 and 7, together, as in an assembly jig, so that the door overlap flange of the inner panel stamping seats in the angle formed by the body of the outer panel and its peripheral flange 34, which, before final assembly, 80 projects laterally to the body of the panel as indicated in dotted lines in Fig. 8. The flange 34 is then crimped down upon the flange 15 forming a firm crimped joinder entirely around the door. If desired, the crimped joinder so formed may be made additionally secure by spot welding at a few places as indicated on each side of the door in Fig. 8. The sub-assemblies are further secured together, as by spot welding the overlapped side walls 26 and 27 of the side portions of the window glass run channels together as indicated in Fig. 8, and by spot welding the side wall 26 at the top portion of the stamping to the jamb rail portion 14 100 at the top of the door as indicated in Fig. 4.

By so constructing and assembling a door made of but a relatively few sheet metal stampings may be assembled with great dispatch, because of the openness of construction so well suited for joinder by welding, and the crimped joints are all readily formed in such manner that the edges of the metal are normally hidden in the final assembly of the door, and because in bringing the parts together they readily fall into place for joinder, and the door when assembled has all the qualities desirable in automobile doors as above pointed out.

What I claim and desire to secure by Letters Patent is:

1. A unitary sub-assembly for sheet metal doors having a window opening therein comprising a unitary face panel stamping extending around the window opening, combined with a unitary glass run channel stamping also extending around the window opening and forming one side of a glass run, and joined to the panel in the margin of the opening.

2. A sheet metal glass run channel stamping for vehicle doors extending entirely around a window opening provided in said doors and being generally of channel section at the sides and presenting transversely 130

- of the plane of the door, the outer side walls of the channel section side portions being extended beyond the inner side walls and adapted to overlap and be secured to a transverse jamb rail portion of the door.
- 5 3. A unitary sub-assembly for sheet metal doors having a window opening therein comprising a unitary face panel stamping extending around the window opening, combined with a unitary glass run channel stamping also extending around the window opening and forming one side of a glass run, and joined to the panel in the margin of the opening by crimping.
- 10 4. A sub-assembly for sheet metal doors having a window opening therein comprising an inner panel stamping extending around the window opening to form the garnishment around said opening arched in section combined with a unitary glass run channel stamping of generally channel section nesting with the portion of the inner panel extending around the window opening and secured thereto in the margins of said opening by crimping and in the outer margins by welding.
- 15 5. A method of assembly of sheet metal doors having a window opening therein and comprised of inner and outer panel stampings extending around the window opening, and inner and outer glass run stampings of generally channel section in their side and top portions, and also extending around said opening, which consists in joining a side wall 30 of said channel section glass run stamping, respectively, to the adjacent edge of its associated panel in the margin of the window opening by crimping the edge of one over the edge of the other to form inner and outer sub-assemblies, and in finally joining said sub-assemblies by crimping the outer margin of the outer panel over the outer margin of the inner panel and joining the overlapped adjacent side walls of the channel section glass 35 run channel stampings.
- 40 6. A method of assembly of sheet metal doors having a window opening therein and comprised of inner and outer panel stampings and inner and outer glass run stampings, each extending around the window opening, and the inner panel stamping forming transverse jamb face portions of the door, which consists in joining each panel stamping to its adjacent glass run channel stamping by crimping their edges together in the margins of the window opening to form sub-assemblies, in joining the inner glass run stamping to the transverse jamb face portion of the inner panel stamping, whereby outer and inner 45 sub-assembly units are formed, and in finally joining said outer and inner sub-assembly units by crimping the panel stampings together in their outer margins and in joining the outer overlapped portions of the glass 50 run channel stampings, as by welding.
7. A sheet metal door having a window opening therein comprising a face panel stamping extending entirely around the window opening and formed in said window opening with an angular seat, and in its side 70 portions with transversely extending jamb face portions, at least one of which is provided with a shoulder, combined with a glass run channel stamping also extending around the window opening and having complementary portions engaging said angular seat and shoulder, and rigidly secured thereto.
8. A sheet metal door having a window opening therein comprising a face panel stamping extending entirely around the window opening and formed in said window opening with an angular seat and having a body portion extended in the plane of the door below said window opening, combined with a glass run channel stamping also extending around the window opening and having complementary angular portions engaging said angular seat and secured thereto, and a bottom edge portion seated against and joined to the body portion of the face panel, 85 thereby forming with said panel a box-section structure below the window opening.
- In testimony whereof I hereunto affix my signature.
